UNITED STATES PATENT OFFICE.

ISIDOR KITSEE, OF PHILADELPHIA, PENNSYLVANIA.

TRANSMISSION OF INDUCED IMPULSES.

No. 861,126.

Specification of Letters Patent.

Patented July 23, 1907.

Application filed October 11, 1906. Serial No. 338,415.

To all whom it may concern:

Be it known that I, ISIDOR KITSEE, a citizen of the United States, residing at Philadelphia, in the county of Philadelphia and State of Pennsylvania, have invented certain new and useful Improvements in Transmission of Induced Impulses, of which the following is a specification.

My invention relates to an improvement in the transmission of induced impulses.

10 It is well known, that if a current of electricity is sent through the primary of a converter or inductorium, a momentary impulse of opposite direction is induced in the secondary and when the flow of the current ceases, a momentary impulse is induced in the secondary of the same direction as the former flow of the current in the primary. These impulses are of comparatively high electro-motive force and their nature may be defined therewith, that the potential does not gradually rise and fall, but its rise to the highest potential 15 is instantaneous and abrupt, and their employment in electric telegraphy was found impractical, for the reason that no means have been found to prevent the mutual induction of aerial conductors and no means have so far been found to prevent them from injuring the insulation of an electric cable.

It is the aim of my invention to so convert these impulses, that the same may be safely and advantageously employed in electric transmission.

In the course of my experiments, I have discovered 30 that, whereas an impulse, such as is induced in the secondary of an inductorium, cannot with safety be transmitted over an insulated line, and cannot be used telegraphically in conjunction with a telephonic impulse in its original form, its employment in telegraphy 35 as well as for other purposes is made practical, if converted in a manner so that the rise as well as fall of potential is a gradual one, and I have discovered that such result can be obtained with the aid of static devices shunting or short circuiting the secondary in 40 which these impulses are generated.

Referring to the drawing, Figure 1 is a diagram of a converting device embodying my invention. Fig. 2 is a diagram illustrating graphically the difference between the unconverted and converted induced impulse. In this figure, 8 represents the unconverted impulse and 9 the impulse converted. It will be seen from this figure, that whereas the converted impulse may be represented by a broadened curve, the unconverted impulse is best illustrated by the nearly straight 45 line or sharp curve.

50 In my experiments, I have found that the time-unit for the passing of these impulses may be increased from one to five, if a large enough capacity is inserted

in the circuit shunting the secondary. The best method of observing the gradual "flattening", so to speak, of the induced impulse is: to insert an adjustable condenser in the shunt and to insert a ballistic galvanometer and an ear-phone in the circuit representing the line of transmission. When the condenser is reduced to the smallest capacity, the movement of 55 the needle is sharply, "jerky", and the ear-phone produces also a sharply defined click, but with the gradual increase of the capacity of the condenser, the movement of the needle becomes a more gradual one and the click in the phone assumes a hollow sound, gradually decreasing in volume, until finally, when the capacity of the condenser is greatly increased, entirely 60 disappearing.

In the drawing, 10 is the line which may be used for 70 electric transmission of intelligence or for the transmission of power; 1 is the inductorium as an entirety; 2 is the primary and 3 the secondary thereof. The primary is here shown as locally connected to a source of current 5 with the interposition of a key 6, but it is obvious that any other source of current than the batteries here shown may be inserted in the circuit; so also may the key 6 be re-placed by other means adapted to operate the electric circuit; 4 are the static means, here shown as a condenser, connected in shunt as to 75 the secondary 3. I have not shown here the means to vary the capacity of such condenser as such means are old and well understood.

I have shown and described herein subject-matter 80 not claimed, but claimed in my co-pending application Serial No. 335780, filed September 22, 1906. 85

Having now described my invention, what I claim as new and desire to secure by Letters Patent is:

1. As an improvement in the art of electrical signaling over a circuit or conductor, the method which consists in producing a sharp electrical impulse, and converting said 90 sharp impulse into a line impulse of relatively great duration.

2. As an improvement in the art of electrical signaling over a circuit or conductor, the method which consists in producing a sharp electrical impulse, storing energy of 95 said impulse in electro-static form, and causing said stored energy to flow to line as an impulse of relatively great duration.

3. As an improvement in the art of electrical signaling over a circuit or conductor, the method which consists in 100 generating a current, changing or interrupting said current, deriving a sharp induced impulse therefrom, and converting said sharp induced impulse into a line impulse of relatively great duration.

4. As an improvement in the art of electrical signaling over a circuit or conductor, the method which consists in generating a current, deriving a sharp induced impulse therefrom, storing energy of said sharp induced impulse in electro-static form, and causing said energy to flow to line as an impulse of relatively great duration. 105

110

5. As an improvement in the art of signaling over a circuit or conductor, the method which consists in producing sharp electrical impulses, controlling the production of said impulses in accordance with the signal to be sent, and converting said sharp impulses into line impulses of relatively great duration.

6. As an improvement in the art of electrical signaling over a circuit or conductor, the method which consists in generating sharp electrical impulses, controlling the production of said impulses in accordance with the signal to

be sent, storing energy of said impulses in electro-static form, and causing said energy to flow to line as impulses of relatively great duration.

In testimony whereof I affix my signature in presence of two witnesses.
